UNITED STATES PATENT OFFICE.

FRANK D. HEALY, OF PLATTSBURG, NEW YORK.

DESIGN FOR A PIN, BROOCH, OR SIMILAR ARTICLE FOR PERSONAL WEAR.

50,416.

Specification for Design.

Patented Mar. 6, 1917.

Application filed December 1, 1916. Serial No. 134,532. Term of patent 14 years.

To all whom it may concern:

Be it known that I, FRANK D. HEALY, a citizen of the United States, residing at Plattsburg, in the county of Clinton and State of New York, have invented a new, original, and ornamental Design for a Pin, Brooch, or Similar Article for Personal Wear, of which the following is a specification.

The accompanying drawing represents a front elevation of a pin, brooch or similar ornamental article adapted for personal wear embodying the design.

I claim:

The ornamental design for a pin, brooch or similar article for personal wear, as shown.

FRANK D. HEALY.

Witnesses:

N. F. JOHNSON,
K. M. ANGELL.
